Inventor,
John Kaltenbach, by
G. Kennedy
Attorney.

UNITED STATES PATENT OFFICE.

JOHN KALTENBACH, OF WATERLOO, IOWA.

SASH FASTENER.

Application filed July 3, 1922. Serial No. 572,686.

To all whom it may concern:

Be it known that I, JOHN KALTENBACH, a citizen of the United States of America, and a resident of Waterloo, Blackhawk County, 5 Iowa, have invented certain new and useful Improvements in Sash Fasteners, of which the following is a specification.

My invention relates to improvements in sash fasteners, and the object of my improvement is to supply means for releasably fastening either or both of a pair of window sashes in adjusted positions as desired.

This object I have accomplished by the means which are hereinafter described and 15 claimed, and which are illustrated in the accompanying drawings, in which Fig. 1 is an elevation of one face of a pair of window sashes and of the casing therefor, parts being sectioned or broken away, said sashes 20 and casing being equipped with the coacting elements of my said fastening means. Fig. 2 is a vertical cross section taken through said casing and sashes looking toward the inner face of the main plate, and Fig. 3 is 25 another vertical cross section of said casing and sashes, but looking toward the outwardly directed face of said main plate. Fig. 4 is an enlarged perspective view of said main plate with the fastener elements mounted 30 thereon. Figs. 5 and 6 are like horizontal cross sections of parts of the casing, showing parts of said sashes, and showing the fastener elements which are respectively mounted on both coactively, and as unengaged in Fig. 5, and as engaged in Fig. 6.

The numeral 8 denotes a window casing of the usual type, containing a pair of glazed window sashes 10 and 11 mounted to move past each other vertically in parallel planes.

40 One vertical jamb has a vertically elongated recess 9, covered by a main plate 1, having on its outwardly directed face a number of longitudinally alined horizontal brackets 3 orificed in line to receive a vertical shaft or rod 4 on which a number of cross-bars 5 are 45 loosely mounted to rock horizontally thereon, independently of each other. Each cross-bar 5 has near its opposite ends like fixed pins which project toward and 50 partially into horizontally elongated slots 2 in the plate 1. Each pin 6 in one vertical row has a short coiled compression-spring mounted thereon and engaged between the plate 1 and the adjacent cross-bar 5. The 55 springs are uncompressed when the pins 6

are as shown in Fig. 5 equally extended into said slots 2.

The numeral 12 denotes a plate which is secured to the edge of the sash 11 which abuts upon the main plate 1 over the row of 60 pins 6 which carry said springs 7, and this plate 12 has a like plurality of horizontally elongated holes 13, of the same size and shape as the holes 2 in the plate 1 and positioned for occasional registration therewith. 65

Upon the top edge of the other sash 10 a hollow boxing 14 is fastened longitudinally with one end close to the main plate 1. This boxing contains a slide-bolt 15, and a portion of the top of the boxing is removed and 70 recessed at 17 at one side, and the bolt 15 has a finger-stud 16 extending angularly therefrom in the open part of the boxing, for manual use in sliding the bolt to and fro toward and into either of the holes 2 in the 75 plate 1 with which it may be placed in alinement when the sash 10 is moved up or down in said casing.

When the lower sash 10 is either in its lowermost position as shown in the figures, 80 or in certain elevated positions, the bolt 15 may be thrust into an alined hole 2, engaging and pushing farther into the recess 9 the alined pin 6, thus rocking the cross-bar 5 only on which this pin is mounted, so that the spring 7 about the opposite pin is compressed while said opposite pin 6 moves into the registering holes 2 and 13 in said overlapping plates 1 and 12. The bolt may then be rocked over to engage its stud 16 with 85 one of the notches 17 in the boxing 14 to secure the fastening elements above mentioned in positions to lock both sashes either closed, or in any adjusted positions.

When the bolt is rocked back, and released, the compressed spring 7 reacts to slide the bolt back, whereby both sashes are unfastened. It is apparent that either or both sashes may thus be held locked in any 90 positions of relative adjustment as desired. 100

Having described my invention, what I claim as new, and desire to secure by Letters Patent, is:

1. The combination of a slide-bolt adapted to be mounted on the lower sash of a 105 window, a plate mounted over a recess in the window-jamb and having longitudinally-alined opposite holes adjacent both its longitudinal edges respectively in the paths of the lower and upper sashes, a plate mounted on 110

the upper sash of the window having a longitudinal row of sockets in its face over one of said rows of holes, and resiliently-controlled rock-bodies mounted in the jamb-recess and having pins extending into the opposite holes in the plate; said slide-bolt when moved toward said plate pushing outwardly the pin alined therewith to rock its rock-body and push the other pin on said 10 rock-body into an alined socket on the plate on the upper sash.

2. The combination of a slide-bolt adapted to be mounted on the lower sash of a window, means for releasably locking said slide-bolt in a desired position of adjustment, a plate mounted over a recess in the window-jamb and having longitudinally-alined opposite holes adjacent both its longitudinal

edges respectively in the paths of the lower and upper sashes, said holes being transversely elongated, a plate mounted on the upper sash of the window having a longitudinal row of sockets in its face over one of said rows of holes, and resiliently-controlled rock-bodies mounted in the jamb-recess and having pins extending toward the opposite holes in said plate, said slide-bolt when moved toward said plate entering an alined hole therein to push outwardly one pin on a rock-body to rock the latter to push the opposite pin thereon into an alined socket in the plate on said upper sash.

Signed at Waterloo, Iowa, this 31st day of May 1922.

JOHN KALTENBACH.
